CLAIM

The ornamental design for a solar fountain, as shown and described.

DESCRIPTION

FIG. 1 is a front view of a solar fountain showing the new design;

FIG. 2 is a back view thereof;

FIG. 3 is a left-side view thereof;

FIG. 4 is a right-side view thereof;

FIG. 5 is a top view thereof;

FIG. 6 is a bottom view thereof; and,

FIG. 7 is a perspective view thereof.

FIG. 8 is a detail view of the portion of the invention encircled in dot-dash lines in FIG. 7.

Broken lines illustrate portions of the solar fountain that form no part of the claimed design. Additional broken lines in FIGS. 7 and 8 designate the detail view areas and form no part of the claimed design.

1 Claim, 8 Drawing Sheets
